PAUL A. GOLLNICK AND FRANK W. BRODERICK, OF CHICAGO, ILLINOIS, ASSIGNEES,
BY MESNE ASSIGNMENTS, TO SELECTOGRAPH COMPANY, OF CHICAGO, ILLINOIS, A
CORPORATION OF ILLINOIS

RECORDING DEVICE FOR ADDRESSING MACHINES

Application filed July 26, 1928. Serial No. 295,447.

This invention relates to recording mechanisms particularly adapted for use in addressing machines for marking the stencils with certain indicia which record the sales efforts, purchases or other items in the history of any case so as to prevent duplication of correspondence with the addressee.

The main objects of this invention are to provide a recording mechanism having improved marking means; to provide improved means for supporting the marker adjacent the path of the stencil; to provide supporting means of this kind which permit adjustment of the marker whereby the recording indicia may be placed in various positions on the margin of the stencil; to provide improved means for supporting and guiding an inking ribbon in the path of the marking element; to provide an improved feeding mechanism for the inking ribbon; to provide a feeding mechanism of this kind having improved reversing means for automatically reversing the feed of the ribbon; and to provide an improved form of operating mechanism for actuating the marker.

An illustrative embodiment of this invention is shown in the accompanying drawings, wherein:

Figure 1 is a top plan of a recording mechanism to which this invention is applied, parts of an addressing machine being also shown.

Fig. 2 is a vertical section of the recording mechanism taken on the line 2—2 of Fig. 1, portions being broken away for the sake of clearness.

Fig. 3 is a front elevation of the same, taken from the right of Fig. 1, and showing certain portions in dotted outline.

Fig. 4 is a vertical section, taken on the line 4—4 of Fig. 2.

Fig. 5 is a detail in elevation of a part of the actuating mechanism whereby the marker is reciprocated.

Figs. 6 and 7 are details showing portions of the actuating mechanism which reciprocates the marker.

Fig. 8 is a fragmentary perspective of the marker.

Fig. 9 is a horizontal section, taken on the line 9—9 of Fig. 2.

Fig. 10 is a vertical section, taken on the line 10—10 of Fig. 3.

Addressing machines having recording devices generally include address bearing strips or stencils which are fed step-by-step along a guideway to a printing mechanism which is adapted to coat with one stencil at a time for making an impression upon an envelope or other sheet material. The main printing mechanism is generally selectively controlled by means of a selector adapted to engage the stencils at a position in advance of the impression member.

In the use of addressing machines, it is frequently desirable to preserve a record indicating the nature of the letters or other matter sent to each addressee so as to prevent duplication of correspondence. By placing the record of each transaction directly upon the stencil it may be conveniently observed by the operator during the operation of the machine and also obviates the expense incident to the keeping of separate record books or cards.

The invention herein shown and described relates particularly to the recording mechanism and, therefore, certain parts of the addressing machine believed unnecessary to a complete understanding of the invention have been omitted from the drawings.

In the form shown, the addressing machine includes a horizontal table 1, and a pair of spaced guide rails 2 and 3 arranged to form a supporting guideway for stencils 4, which are fed step-by-step along the guideway by an intermittently movable conveyer chain 5 having lugs 6 engaging apertures in the stencil frame as fully described in Patent No. 1,666,171 issued April 17, 1928.

Stencils commonly employed in addressing machines comprise a tissue address-bearing portion 7 mounted in a stiff narrow marginal frame 8.

The improved recording mechanism herein shown is adapted to place the marks directly upon the narrow margin of the stencil and, therefore, it is not necessary to employ stencils having specially formed record portions.

In the construction shown, the improved recording mechanism comprises a support,

on which is mounted a marker 10 adapted to coat with an inking ribbon 11, which is fed by an improved feeding mechanism 12 arranged to be actuated through the movement of the marker. The marker is reciprocated by an improved operating mechanism 13.

In the form shown, the support includes a carriage 14, which is slidable on the stencil guideway and which carries an adjustable standard 15 forming a mounting for the marker.

The carriage 14 includes a base part 16 having a central opening 17, through which extends the marker and the running part of the ribbon 11.

Depending from the base part 16, is a pair of bearing members 19 and 20 for slidably supporting the unit 14-15 on the stencil guideway, so as to permit the marker to be adjusted longitudinally of the stencil, whereby the record marks may be placed in various positions on the sides of the stencil frame 8.

The member 19 slidably embraces the guide rail 2 and the member 20 slidably embraces a plate 21 mounted on the upper edge of the rail 3. The plate 21 bears suitable gage markings 22 adapted to register with one edge of the bearing member 20 to indicate the position of the marker with respect to the stencil. Mounted in the bearing member 20, is a set screw 23 adapted to engage the plate 21 to secure the carriage 14 against movement.

Formed on the base part 16, is a pair of upstanding lugs 24 and 25 in which is mounted a pair of studs 26 and 27, respectively, for pivotally supporting a part 28 of the operating mechanism 13, as hereinafter described.

The standard 15 includes a bearing part 29 and a bracket 30. The part 29 has a post 31 provided with a central bore 32 in which the marker reciprocates. Formed on the lower end of the post 31, is a plate 33 provided with an annular flange 34, which is rotatably mounted in the opening 17 of the carriage 14, so as to permit the marker to be shifted transversely of the stencil guideway. Formed in the plate 33, is an opening 35 through which the inking ribbon extends.

The bracket 30 is rigidly secured to the plate 33 by screws 36. Formed on the upper end of the bracket 30, is an offset plate 37 having bosses 38 and 39, hangers 40 and 41 and an arm 42 integrally formed thereon for supporting certain portions of the ribbon feeding mechanism 12, as hereinafter described.

The entire unit 15 is adapted to be secured against rotation relative to the carriage 14 by means of a set screw 43 mounted on the base part 16 and adapted to engage

either one of a pair of notches 44 formed in the periphery of the plate 33.

In the form shown, the marker 10 includes a vertically disposed reciprocable plunger 45, slidable in the post 31, and having a block 46 rigidly mounted on the lower end thereof for carrying a type element 47, which may be seated in either one of a pair of apertures 48 formed in the block. The apertures 48 are located at different distances 75 from the plunger 45, so as to permit the type element 47 to be adjusted relative to the width of the stencil frame 8 for making two rows of marks.

Embracing one end of the block 46, is a wire guide 49 arranged to form a pair of loops 50 for guiding the inking ribbon 11.

Mounted on the upper end of the plunger 45, is a head 51, which is adjustably secured thereto by nuts 52 and 53 threaded on the plunger. Formed in the head 51, is a pair of recesses 54, in which is seated a pair of depending arms 55 secured to the head by screws 56. Formed in the arms 55, adjacent the lower ends thereof, are notches 57 for receiving a portion of the operating part 28.

In the specific form shown, the ribbon 11 is supported on a pair of spools 58 and its running part extends through the guide loops 50, so as to pass across the path of the type element 47.

The spools 58 are mounted on shafts 59, which are journaled in the bosses 38 and 39. The spools 58 are secured against axial movement by a bar 60 supported on the inner ends of the shafts 59 and springs 61 embracing the shafts. The springs 61 bear between the spools and the bosses 38 so as to yieldingly resist rotation of the spools.

The improved ribbon feeding mechanism 12 includes a shaft 62, journaled in the hangers 40 and 41 and having pinions 63 and 64 adapted to be shifted into engagement with gears 65 and 66, respectively, which are fixed on the outer ends of the shafts 59. The pinions 63 and 64 are arranged so that when either one of them engages the adjacent gear, the other pinion is disengaged, as shown in Fig. 1. The pinions 63 and 64 are shifted into and out of engagement with the gears by the movement of the shaft 62 axially in the hangers 40 and 41, as hereinafter described.

Formed in the shaft 62 adjacent one end thereof, is a pair of notches 67 for receiving a ball 68 resiliently urged into engagement with either of the notches by a spring 69 mounted in a housing 70 formed on the hanger 41. The tension of the spring 69 may be varied by a screw 71 bearing against one end of the spring.

Fixed on the shaft 62, is a ratchet 72 adapted to be rotated step-by-step by means of a pawl 73 pivotally mounted on an oscillating arm 74. One end of the arm 74 is journaled on the shaft 62. Mounted on the other end

of the arm 74, is a pin 75, which engages the bifurcated end 76 of an arm 77. The arm 77 is secured to the plunger head 51 by a screw 78, so that, upon each return stroke of the plunger 45, the arm 74 is moved upwardly to feed the ratchet 72 one step, thereby partially rotating the shaft 62 and one of the ribbon spools 58.

The ratchet 72 is secured against backward movement by a spring detent 79, which is rigidly secured to a cross piece 80 integrally formed on the arm 42.

The ribbon feeding mechanism also includes improved reversing means for axially shifting the shaft 62 so as to reverse the rotation of the ribbon spools.

In the form shown, the reversing means includes a slide bar 81 having arms 82 at its ends for supporting a pair of brackets 83 in which are journaled rollers 84 adapted to ride on the ribbon rolls for shifting the bar 81 longitudinally. The bar 81 is slotted to receive studs 85, mounted on the plate 37.

Mounted on the bar 81, is a pair of spaced pins 86, which project outwardly through an opening 87, formed in the plate 37, for oscillating a rocker 88.

The rocker 88 is substantially U-shaped and is pivoted to a pin 89 mounted on the cross piece 80 of the arm 42. One arm of the rocker 88 is longer than the other and is provided with a slot 90 for receiving a pin 91 mounted on a sleeve 92, which loosely embraces the shaft 62. The sleeve 92 is located between the ratchet 72 and a collar 93 fixed on the shaft 62, so that the axial shifting of the sleeve 92, under the action of the rocker 88, shifts the shaft 62 axially.

Mounted on the lower end of the rocker 88, is a pin 94, which is secured to the lower end of a spring 95. The upper end of the spring 95 is secured to a pin 96 mounted on the plate 37. The spring 95 is arranged to cause a quick throw of the rocker 88 as soon as one of the pins 86 has shifted the rocker beyond the vertical position. The slot 90 is of sufficient length so that the pin 91 is not engaged until the rocker is acted upon by the spring 95.

In the embodiment illustrated, the improved operating mechanism 13 includes a continuously driven operating shaft 97 arranged to drive an accumulator 98, which is adapted to actuate the marker 10 after the accumulator has been set by improved setting means.

The shaft 97 is driven by any suitable means, not shown, and one end thereof is journaled in a bearing 100 formed on a frame 101, which is secured to the table 1 by bolts 102.

The accumulator 98 includes a gear 103 fixed on the shaft 97 and adapted to mesh with a gear 104 formed on a drum 105 which is journaled in the frame 101. The gear 104

is considerably larger than the gear 103 and both gears are mutilated so that the accumulator does not become effective for actuating the plunger 10 until the stencil has moved a plurality of steps after the setting or selecting operation as hereinafter described.

Formed in the drum 105, is a plurality of transversely disposed slots 106, in which detent pins 107 are seated. The pins 107 are secured against withdrawal from the slots by keys 108 which engage recesses 109 formed in the pins.

The detent pins 107 are axially shiftable, and are adapted to be projected beyond one face of the drum 105 by the improved setting means, for actuating the operating part 13.

The setting means includes a sleeve 110 loosely mounted on the shaft 97 and adapted to be rotated through the action of a selector mechanism, not shown, which coacts with each stencil as the stencil reaches a certain position in the guideway.

Fixed on the sleeve 110, is a gear 111 meshing with a gear 112 fixed on a shaft 113, which is journaled in the frame 101 and in a bearing 114 of the table 1. Fixed on the shaft 113, is a rotary cam 115 having a cam surface 116, which is adapted to engage any one of the pins 107 for projecting it axially beyond the opposite face of the drum 105, where it is adapted to actuate the operating member 13 during rotation of the drum 105.

In the construction illustrated, the operating part 13 includes a lever 117, which is pivoted on a stud 118 mounted on a depending lug 119 which is formed on the frame 101. The upper end of the lever 117 has a shoulder 120, which is adapted to engage one of the pins which has been projected into operative position by the cam 115.

Acting between the lever 117 and a pin 121 on the frame 101, is a spring 122, which is arranged to normally urge the lever rearwardly for holding the shoulder 120 in position to engage one of the detents 107.

Pivots connected to the lever 117, is a link 123, which is also pivoted on a rod 124 mounted on a rocker member 125. The rocker member 125 is substantially U-shaped and is pivoted on a rod 126, which is supported in the lug 119 and in another depending lug 127 formed on the frame 101.

Slidably connected to the rod 124, is a link 128, which is pivotally connected to a pin 129 supported in a pair of lugs 130 formed on the oscillating member 28. The link 128 is adapted to slide on the rod 124 longitudinally of the stencil guideway so as to permit the marking unit to be shifted longitudinally of the stencils while still maintaining proper connection and relation to the operating mechanism.

The member 28 is in the form of a rock

shaft journaled on the studs 26 and 27 and having arcuate fingers 132 which engage the notches 57 of the marker.

The fingers 132 are restored to the initial position illustrated in Fig. 2 by the action of the spring 122. To supplement the spring 122, the lever 117 is provided with cam surfaces 133 adapted to coact with one of the pins 107 after the pin has become disengaged from the shoulder 120. In the event the spring 122 is broken, the cams 133 and coacting pin will positively restore the lever 117 to initial position.

A cam surface 134 is located adjacent the cams 133 in position to engage the extremity of the detent pin 107 for restoring the pin to its inoperative position with respect to the drum 105.

In operation, the stencils 4 are fed step-by-step along the guideway, by the chain conveyor 5, so as to be successively presented to the selector and printing mechanisms, not shown, and then to the improved recording mechanism. Only those stencils which are in a given selection are acted upon by the printing and recording mechanisms. The other stencils merely pass through the machine.

When a selected stencil reaches selecting position, the selector is set thereby and causes the rotation of the sleeve 110, which actuates the cam 115 through the gears 111 and 112. During the operation of the machine, the drive shaft 97 operates continuously for driving the drum 105. Upon rotation of the cam 115, it engages one of the detent pins 107 and pushes it into operative position where it may be carried by the rotating drum 105 into engagement with the lever 117.

Movement of the lever 117, under the action of the pin 107, drives the marking plunger 45 downwardly through the action of the links 123 and 128 and the rocker member 28. When the pin 107 passes beyond the shoulder 120, the lever 117 and marking plunger 45 are restored to initial position through the action of the spring 122 and cams 133.

With this improved construction and arrangement of parts, the lever 117 is not actuated by the accumulator until the selected stencil has moved a plurality of steps following the setting action and the marker element 47 is not lowered until the selected stencil reaches recording position.

Upon the upstroke of the plunger 45, the lever arm 74 is shifted to operate the ratchet 72 for feeding the ribbon 11 one step. During the feeding of the ribbon 11, the slide 81 is slowly shifted so as to move the rocker arm 88. When the rocker arm 88 is shifted beyond the vertical position, it is acted upon by the spring 95 for quickly shifting the shaft 62 axially to reverse the feeding action of the spools 58.

To shift the marker longitudinally of the stencil, the set screw 23 is loosened to permit

the carriage 14 to be moved along the guide rails 2 and 3. When the carriage 14 moves along the rails 2-3, the link 128 slides on the rod 124, thereby constantly maintaining the marker in proper relation with the operating mechanism. To shift the marker transversely of the guideway, the set screw 43 is loosened to permit rotation of the support 15 on the carriage 14. With this improved form of marker, the indicia may be placed on all sides of the marginal frame 8 and in several rows if desired.

Although but one specific embodiment of this invention has been herein shown and described, it is to be understood that numerous details of the construction shown may be altered or omitted without departing from the spirit of this invention as defined by the following claims.

We claim:

1. In a device of the class described, the combination with a guideway for stencils, a recording mechanism adapted to mark certain indicia upon the stencils, and operating means including an accumulator arranged to actuate said recording mechanism.

2. The combination with a marking element, of actuating means arranged to operate said marking element, a rotatable member, a detent carried by said rotatable member and adapted to engage said means for actuating said element, a cam adapted to move said detent into effective position for engagement with said means, and means for retracting said detent.

3. The combination with a reciprocable marking element, of an operating mechanism therefor, comprising an oscillating member, a rotatable member, a detent carried by said rotatable member and shiftable thereon so as to be adapted to engage and actuate said oscillating member during the rotation of said rotatable member, and a pair of cams arranged to shift said detent respectively into and out of its operative position relative to said rotatable member.

4. The combination with a reciprocable marking element, of an operating mechanism therefor comprising an oscillating member, a rotatable member, a plurality of pins carried by said rotatable member and shiftable axially thereon, so as to be adapted to engage and actuate said oscillating member during the rotation of said rotatable member, a rotatable cam adapted to shift said pins into operative position relative to said rotatable member, and a cam on said oscillating member adapted to retract said pins.

5. In a device of the class described, the combination with a support for stencils, a reciprocable marker movable toward and away from said support and adjustable longitudinally thereof, of an actuating element, and means actuated by said element and arranged to operate said marker, said means

being adjustable on said actuating element longitudinally of said support so as to be adapted to operate said marker in any position of the latter.

5 6. In a device of the class described, the combination with a support for sheets, a reciprocal marker movable toward and away from said support and adjustable longitudinally thereof, of an operating mechanism for said marker including an oscillating member, and means slidably connected to said oscillating member and arranged to operate said marker, said means being shiftable longitudinally of said support.

10 15. 7. A device of the class described comprising a guideway for stencils, a carriage supported on said guideway and slidable longitudinally thereof, a support mounted on said carriage, a reciprocal marker mounted on said support and movable toward and away from said guideway, said support being rotatable on said carriage on an axis substantially normal to the plane of said guideway for shifting said marker laterally of said guideway, and mechanism for reciprocating said marker.

20 30. 8. An addressing machine comprising a horizontal guideway for supporting and guiding stencils through a definite path, a recording element located on one side of said guideway for marking the stencils, and means for supporting said element, said supporting means being movable in the direction of the length of said guideway to adjust said recording element longitudinally of the stencils, part of said supporting means being rotatable on an axis substantially normal to the plane of said guideway for adjusting said recording element laterally of the stencils.

35 40. 9. An addressing machine comprising a horizontal guideway for supporting and guiding stencils through a definite path, a recording element located on one side of said guideway for marking the stencils, means for supporting said element, said supporting means being slidable in the direction of the length of said guideway to adjust said recording element longitudinally of the stencils, part of said supporting means being rotatable on an axis substantially normal to the plane of said guideway for adjusting said recording element laterally of the stencils, and mechanism for vertically reciprocating said element.

45 55. 10. An addressing machine comprising a horizontal guideway for supporting and guiding stencils through a definite path, a recording element located on one side of said guideway for marking the stencils, means for supporting said element, said means being slidable in the direction of the length of said guideway to adjust said recording element longitudinally of the stencils, part of said supporting means being rotatable on an axis substantially normal to the plane of said

guideway for adjusting said recording element laterally of the stencils, mechanism for vertically reciprocating said element, and means for feeding the stencils along said guideway to successively position them adjacent said recording element.

50 55. 11. A device of the class described comprising a guideway for stencils, a carriage supported on said guideway and slidable longitudinally thereof, a support mounted on said carriage, a reciprocal marker mounted on said support and movable toward and away from said guideway, said support being rotatable on said carriage for shifting said marker laterally of said guideway, releasable means for securing said carriage against movement, other releasable means for securing said support against rotation, and mechanism for reciprocating said marker.

60 65. 12. A device of the class described comprising a guideway for stencils, a movable recording element for marking the stencils, means for actuating said recording element, an accumulator for operating said actuating means, and setting mechanism adapted to actuate said accumulator.

70 75. 13. A device of the class described comprising a guideway for stencils, a movable recording element for marking the stencils, means for actuating said recording element, an accumulator adapted for rotation, a detent carried by said accumulator and movable into and out of position to actuate said means, and setting mechanism adapted to move said detent into operative position relative to said actuating means.

80 85. 14. A device of the class described comprising a guideway for stencils, a movable recording element for marking the stencils, means for actuating said recording element, a pair of coacting mutilated gears, a detent carried by one of said gears and movable into and out of position to actuate said means, and setting mechanism adapted to move said detent into operative position relative to said actuating means.

90 95. 15. A device of the class described comprising a guideway for stencils, a movable recording element for marking the stencils, means for actuating said recording element, a pair of coacting mutilated gears, one of said gears being driven continuously, a detent carried by the other of said gears and movable into and out of position to actuate said means, and setting mechanism adapted to move said detent into operative position relative to said actuating means.

100 105. 16. A device of the class described comprising a guideway for stencils, a movable recording element for marking the stencils, means for actuating said recording element, a drive shaft, a driven shaft, a pair of coacting mutilated gears, one of said gears being fixed on said drive shaft, a sleeve loose-
